DESIGN FOR A BAND SAW

William J. Merrigan, Los Angeles, Calif., assignor
to Herberts Machinery Co., Ltd., Los Angeles,
Calif.

Application January 23, 1935, Serial No. 55,018

Term of patent 14 years

To all whom it may concern:

Be it known that I, William J. Merrigan, a citizen of the United States, residing at Los Angeles, in the county of Los Angeles and State of California, have invented a new, original, and ornamental Design for Band Saw, of which the following is a specification, reference being had to the accompanying drawings forming part thereof.

Fig. 1 is a view in side elevation of the band saw embodying my design.

Fig. 2 is a view in front elevation of the same. Fig. 3 is a view in side elevation of the band saw, the same having been taken from the opposite side thereof from that shown in Fig. 1.

I claim:

The ornamental design for a band saw as shown.

WM. J. MERRIGAN.
